UNITED STATES PATENT OFFICE.

HERBERT E. MARKS, OF SEWICKLEY, PENNSYLVANIA.

ROOF CONSTRUCTION.

Application filed March 9, 1922. Serial No. 542,278.

To all whom it may concern:

Be it known that I, HERBERT E. MARKS, a citizen of the United States, and a resident of Sewickley, in the county of Allegheny and State of Pennsylvania, have invented a new and useful Improvement in Roof Constructions, of which the following is a specification.

The invention relates to roof structures of the character disclosed in my Patent No. 1,398,079, or in other words to roof structures which include flanged angle members laid upon roof purlins to form a frame, plaster boards or their equivalent supported by the flanges of the angle members, and a body of cementitious material such as gypsum molded upon and bonded to the plaster boards, the plaster boards affording forms or centering for the cementitious material while being molded.

An object of the invention is to provide a roof which may be constructed of inexpensive materials and easily and cheaply erected, which is fireproof, an efficient heat insulator, and light in weight but nevertheless strong and durable. A further object is to improve the roof structure of my said patent.

The invention is applicable to roofs for various purposes, whether flat, sloping, hipped or otherwise irregularly shaped. In the accompanying sheet of drawings it is illustrated in its applicability to a plane section of a roof. Fig. 1 is a vertical section of the preferred form of roof, taken on a plane transverse to the purlins; Fig. 2 a vertical section taken at right angles to Fig. 1, the plane of view being indicated by the line II—II, Fig. 1; Fig. 3 a plan view of the roof showing portions of its several layers removed; and Figs. 4 and 5 sections corresponding to Fig. 1 showing modifications of construction.

The roof may be supported by any suitable frame construction, of which no part is illustrated except purlins 1, which, as shown, may be in the form of channel beams. Obviously the frame and purlins can be of any material, character or design, depending upon the kind and size of the roof. The purlins, in the case of a sloping roof, run parallel to the eaves and ridge, as usual.

Supported on the purlins and running at right angles thereto, and consequently run-

ning from ridge to eave in a sloping roof, are a plurality of angle members 2, which may take the form of T-bars resting with their base flanges on the purlins and suitably secured thereto with their legs projecting upwardly. These T-bars form the base or frame of the roof structure proper and are spaced sufficiently close to each other that the distance between them can be bridged by ordinary sizes of plaster boards 3, which are familiar articles of commerce, generally composed of gypsum or the like and generally quite thin, usually about three-eighths of an inch in thickness. The plaster boards are supported with their side edges resting upon the horizontal flanges 4 of the T-bars 2, as shown in Figs. 2 and 3, and may be of any suitable length.

The construction thus far explained is similar to that disclosed in my said Patent No. 1,398,079. In the specific arrangement illustrated in the patent the contiguous ends of adjacent plaster boards are supported on small flanged bars extending between and resting upon the flanges of the T-bars. In the present construction these small cross angle bars are dispensed with, and in lieu thereof other plaster board members are so arranged so as to prevent downward sagging of the unsupported ends of the plaster boards.

One layer of plaster boards 3 rests directly upon the flanges 4 of the T-bars 2, and the joints where adjacent ends of plaster boards 3 meet are overlapped by other plaster boards. As shown in Figs. 1, 2 and 3, additional plaster boards 5 are preferably arranged in a second layer coextensive with the plaster boards 3, but laid so as to break joints with the latter. In the form shown in Fig. 4 relatively narrow sections of plaster boards 5^a overlap the joints between the main plaster boards, whereas in the modification shown in Fig. 5 the additional plaster board sections 5^b underlie such joints. In all forms the additional plaster boards are preferably cemented to the main layer of plaster boards. This may be done by spreading between the surface of the boards a thin layer of the cementitious material of which the roof slab is formed.

If desired, metal reinforcement may be interposed between the two layers of plaster boards, as shown at 6 in Figs. 1, 2 and 3, the reinforcement being light wire

mesh which is completely embedded in the layer of cementitious material between the upper and lower plaster boards.

The plaster boards 3 and 5, 3 and 5^a or 5 and 5^b when placed in the manner described, especially when cemented together, form a sufficiently rigid form or centering for the molding of the roof slab directly thereon, and also serve as the lower base 10 of the roof slab. The roof slab is formed from suitable cementitious material, preferably gypsum, which is mixed with the proper proportion of water, and then molded directly in place, that is, is poured upon 15 the centering formed by the plaster boards 3 and 5. The composition of this cementitious material is preferably the same as, or similar to, that of the plaster boards. It is such that when poured in place it 20 bonds onto the plaster boards, so that the latter and the solidified cementitious material forms a continuous unitary or monolithic slab 7 of such thickness as to overlie to a material depth the tops of the T-bars 2.

The slab is preferably reinforced by embedding in the cementitious material suitable metallic reinforcement 8, such as light metallic lath, wire mesh, or the like. To 30 effectively resist the strains in the slab, this metallic reinforcement is held in such position that when embedded in the solidified cementitious slab it will lie near the bottom of the slab at points intermediate 35 the purlins 1 and near the top of the slab at points above the purlins. Such positioning of the metallic mesh may be secured by providing holes in the upstanding legs of the T-bars 2, through which heavy wire 40 or similar rods may be threaded from side to side of the roof to hold the metallic mesh in place. For instance, as shown in Figs. 1 and 3, one set of such wires or rods 9 are threaded through holes located quite low 45 down to hold the reinforcement down substantially in contact with the plaster boards at points intermediate the purlins, while another series of rods 10 are threaded through holes above the purlins near the tops of 50 the vertical legs of the T-bars 2 to hold the reinforcement up at points above the purlins. This metallic mesh reinforcement may consist of continuous strips extending from the eaves to the ridge of the roof, or, 55 in the case of a flat roof, from edge to edge thereof; or it may be composed of a number of pieces, the ends of which are overlapped so that when embedded in the cementitious material it has the same reinforcing effect as a continuous strip. Also, 60 if desired, the edge portions of the metallic reinforcement may be bent upwardly and made to overlap the upper edges of the T-bars 2, as shown at 11, Fig. 3, so as to 65 secure a continuous transverse tie. The

cementitious material which is poured on the centering plaster boards 3 readily passes through this metallic mesh and bonds to it and to the plaster boards.

In Fig. 3 there are shown three panels 70 of the roof in various stages of construction. The lower panel shows the T-bars 2 resting upon the purlins 1. At the right of the center panel the lower layer of plaster boards 3 are shown resting upon 75 the horizontal flanges 4 of the T-bars, at the center of this panel the reinforcement 6 is indicated, while the left portion of the panel shows the second layer of plaster boards lying on top of the lower layer with alternating joints. In the upper panel the slab reinforcement 8 is indicated as being positioned by the rods 9 and 10 extending through the vertical legs 2 of the T-bars.

The roof described is of simple construction, is easy and cheap to erect and is light. Because the entire structure, including the plaster boards, forms a monolithic slab which is reinforced for its entire length and width, the structure is capable of standing 90 a very considerable load. The slab is reinforced not only by the metallic mesh described, but also by the T-bars which become thoroughly embedded in and bonded to the cementitious material. Consequently these 95 T-bars can be of light cross section and the slab of minimum thickness. The plaster boards not only form the bottom of the slab, but also serve as a centering, so that the usual centering or forms for erecting roofs 100 of this kind can be entirely dispensed with, thus making a great saving in cost of erection. By having a double thickness of plaster boards, or at least having the joints of the main plaster boards overlapped by 105 sections of plaster boards, and particularly when these are cemented together, the plaster boards are given such rigidity that they do not sag under the load of the wet cementitious material when placed on them. If the 110 plaster boards are cemented together and the cement allowed to set before applying the cementitious material, the plaster boards will have sufficient rigidity, especially when reinforced by the metallic mesh 6, to support 115 workmen and thus dispense with the necessity of having boards on the roof for workmen to walk on.

The top surface of this roof structure 120 may be suitably waterproofed and finished in any well known or desired manner, such as by applying a coating of asphaltum surfaced with gravel.

I claim:

1. A roof of the character described comprising a frame, a series of plaster-board supporting members carried by said frame, a layer of plaster boards having their oppositely disposed sides supported by said members, additional plaster boards over- 130

lapping and strengthening the contiguous ends of said layer of plaster boards, and a cementitious body moulded on the plaster boards and bonded therewith and thereby forming a continuous monolithic roof slab including the plaster boards.

2. A roof of the character described comprising a frame, a series of plaster-board supporting members carried by said frame, 10 a layer of plaster boards having their oppositely disposed sides supported by said members, additional plaster boards overlapping the contiguous ends of said layer of plaster boards and cemented thereto, and a 15 cementitious body moulded on the plaster boards and bonded therewith and thereby forming a continuous monolithic roof slab including the plaster boards.

3. A roof of the character described comprising a frame, a series of plaster-board supporting members carried by said frame, 20 a layer of plaster boards having their oppositely disposed sides supported by said members, a second layer of plaster boards 25 laid upon said first-named layer with joints alternating therewith, and a cementitious body moulded upon the plaster boards and bonded therewith, thereby forming a continuous monolithic roof slab including the 30 cementitious body and plaster boards.

4. A roof of the character described comprising a frame, a series of plaster-board supporting members carried by said frame, 35 a layer of plaster boards having their oppositely disposed sides supported by said members, a second layer of plaster boards laid upon and cemented to said first-named layer with joints alternating therewith, a light metallic reinforcement between said 40 layers of plaster boards, and a cementitious body mounted upon the upper layer of plaster boards and bonded therewith, thereby forming a continuous monolithic roof

slab including both layers of plaster boards, the metallic reinforcement and the cementitious body.

5. A roof of the character described comprising purlins, metal angle members supported on the purlins and having oppositely projecting flanges, a layer of plaster boards supported on said flanges, rods above the purlins supported by the upper portions of said angle members, rods intermediate adjacent purlins supported by the lower portions of said angle members, metal reinforcing fabric extending over said first-named and below second-named rods, and a cementitious body moulded around said fabric and on the plaster boards and bonded therewith, thereby forming a continuous 60 monolithic roof slab including the plaster boards, cementitious body and metallic reinforcement.

6. A roof of the character described comprising purlins, metallic angle members supported on the purlins and having oppositely projecting flanges, a layer of plaster boards supported on said flanges, a second layer of plaster boards laid upon and cemented to first-named layer having joints 70 alternating therewith, a light metallic reinforcement between said layers in plaster boards, rods above the purlins supported by the upper portions of said angle members, rods intermediate adjacent purlins supported 75 by the lower portions of said angle members, metal reinforcing fabric extending over said first-named and below said second-named rods, and a cementitious body moulded around said fabric supported by said rods 80 and on the plaster boards and bonded therewith.

In testimony whereof, I sign my name.
HERBERT E. MARKS.
